CLAIM

The ornamental design of a dust collector for a sander, as shown and described.

DESCRIPTION

FIG. 1 shows a perspective view of a dust collector for a sander, embodying my new design;

FIG. 2 shows a right view of the dust collector shown in FIG. 1;

FIG. 3 shows a front view of the dust collector shown in FIG. 1;

FIG. 4 shows a left view of the dust collector sander shown in FIG. 1;

FIG. 5 shows a back view of the dust collector sander shown in FIG. 1;

FIG. 6 shows a top view of the dust collector shown in FIG. 1; and,

FIG. 7 shows a bottom view of the dust collector shown in FIG. 1.

The broken lines depict portions of the dust collector for a sander in which the design is embodied that form no part of the claimed design.
